JOHN C. ROSS, OF ELYRIA, OHIO, ASSIGNOR TO THE ROSS STAMPING COMPANY, OF ELYRIA, OHIO, A CORPORATION OF OHIO.

GRIP-HANDLE FOR IMPLEMENTS.

No. 869,213.

Specification of Letters Patent.

Patented Oct. 22, 1907.

Application filed March 21, 1907. Serial No. 363,555.

To all whom it may concern:

Be it known that I, JOHN C. Ross, a citizen of the United States, residing at Elyria, in the county of Lorain and State of Ohio, have invented certain new and 5 useful Improvements in Grip-Handles for Implements, of which the following is a specification.

My present invention relates to handles for hand implements, and its object is to provide a D-shaped handle for shovels, spades, scoops and other implements, 10 formed completely from a single sheet of metal. This being accomplished, the advantages of additional strength per unit of weight of material employed, durability, and low cost of manufacture, follow as natural corollaries under present conditions of the availability 15 and comparative cost of materials.

The method of making the implement handle described herein, and its application to certain tools will be more fully understood by reference to my applications filed herewith, entitled, "Method of making 20 shovels," Serial No. 363,557, and "Shovel," Serial No. 363,556.

The handle of my present invention may be attached to any desired form of blade, fork, or other tool, in any suitable way; but, considered simply as a handle, it is 25 illustrated in the accompanying drawings, wherein

Figure 1 is a plan of a handle blank as cut from sheet metal. Fig. 2 is a view of said blank partly formed into a handle. Fig. 3 is a rear view of a handle completed. Fig. 4 is a side view, and Fig. 5 is a front view of a handle as in Fig. 3. Fig. 6 is a view of the side opposite to that shown in Fig. 4, showing also a modification of the form of the grip end.

The reference letter *a* indicates a blank cut from sheet metal with an outline similar to that shown in Fig. 1. The preferable material used is low carbon sheet steel, and it is economical to employ dies which are mounted in a press capable of cutting out several blanks in one operation. The metal of the blank may be of a uniform thickness throughout, or of variable 40 thickness.

The body portion *d* of the blank is bent and rolled up lengthwise into a tube, which may be either straight or bent crosswise, according to the construction of the complete implement for which the handle is intended.

45 The rectangular termination *f* is also rolled up longitudinally to form a tube which ordinarily is cylindrical, but which may be varied to suit conditions of service, as, for example, the form shown in Fig. 6 which is intended for a tamping shovel handle. It is preferred to 50 form the tubes *d* and *f* respectively in two operations between dies, the first operation bending the flats so that their cross sections are U-shaped, and the second operation completing the tubes.

As shown in Fig. 1, an elongated neck *b* connects the 55 parts *d* and *f*, and a corresponding arm or tongue *e* pro-

jects from the part *d* parallel with the neck *b*. Apertures *c* and *g* are punched in *b* and *e* respectively, and a recess *h* is formed in the end of the arm *e*. These apertures and recess are located and sized to receive the respective ears *i*, *m* and *j*, which project from the rectangular portion *f*. After the tube *d* is formed, and preferably while it is still held firmly between its forming dies, the arms *b* and *e* are bent and spread apart, as shown in Fig. 2. These arms may be spread and formed by a die moving lengthwise against the dies employed for completing the formation of the tube *d*. The arm *b* is then bent at its junction with the tubular grip-piece *f*, so that the latter is brought down and sprung into place between the arms *b* and *e* with the ear *i* projecting through the aperture *c*, the ear *m* inserted 60 through the aperture *g*, and the ear *j* lying in the recess *h*. The grip-member *f* in Fig. 2 is shown partly bent down, and the remaining figures show it in completed position. The arms *b* and *e* are then pressed close to the ends of the grip-piece *f*, and the ears *i*, *j* and *m* bent 65 over and pressed or hammered down against said arms, as shown in Figs. 3, 4, 5 and 6, thereby completing a rigid D-shaped grip handle.

In the construction set forth, it is seen that the tubular handle portion *d* is formed of an integral body of 80 sheet metal, which may be welded, brazed, or otherwise held together, if desired, along its single seam *l* to insure the maximum strength. Moreover, the grip-member is attached to the side pieces of the D-handle by means of lugs which pass entirely through the body 85 of the latter, and secure the parts firmly in place, rather than by depending exclusively upon a cross-section of metal which has been subjected to a bending strain, for obtaining such attachment. The edges of the joint *k* in the grip-piece may also be welded or brazed together, 90 but in the cheaper grades of handles this operation may be dispensed with. Thus, a rough implement handle having a D-shaped grip-handle is produced from a single blank of sheet metal, being integral and substantial in all its parts; and all that remains to be done is to 95 smooth and finish it if desired, and attach it by any suitable means to any implement for which it is adapted.

I further point out and distinctly claim as my invention—

1. In an implement handle integrally formed of sheet metal, a tubular handle portion having a single seam, side arms of a grip handle branching therefrom, and a grip-piece connecting said side arms, substantially as set forth.

2. In an integral implement handle, the combination 105 with a tubular handle portion formed of an integral sheet of metal having a single vertical seam, of terminals forming side pieces for a D-handle integral therewith, and a tubular grip-member integral with one of said side pieces and extending transversely thereof, the same being secured 110 to the opposite side piece, substantially as set forth.

3. In an implement handle integrally formed of a single

sheet metal blank, a tubular handle portion having a single seam, side arms of a grip handle branching therefrom, a grip-piece connecting said side arms, and means for holding said grip-piece to said side arms, substantially as set forth.

5. 4. In an implement handle integrally formed of a single blank of sheet metal, a tubular handle portion having a single seam, side arms of a grip handle branching therefrom, a tubular grip-piece integral with one of said side arms, and means for securing said grip-piece to the other side arm, substantially as set forth.

10. 5. In an implement handle formed of single blank of sheet metal, a tubular handle portion, a pair of side arms of a grip handle branching therefrom, a tubular grip-piece integral with one of said side arms, and projecting ears of said grip-piece adapted to engage the said side arms to hold the parts rigidly in place, substantially as set forth.

15. 6. In an implement handle formed of a single blank of sheet metal, a tubular handle portion, a pair of side arms of a grip handle branching therefrom, a tubular grip-piece integral with one of said side arms, and ears

projecting from the ends of said grip-piece engaging suitable apertures in the respective side arms and bent down to overlap said side arms, substantially as set forth.

20. 7. An implement handle formed complete of a single sheet metal blank, comprising a tubular handle portion, side arms of a grip handle integral with and branching from one end of said handle portion, a tubular grip-piece having one end integral with one of said side arms, a dowel connection between the grip-piece and the attached side arm, and projections upon the free end of the grip-piece engaging suitable apertures in and overlapping the unattached side arm, substantially as set forth.

25. In testimony whereof I affix my signature in the presence of two subscribing witnesses at Cleveland, Ohio, this 6th day of March, 1907.

JOHN C. ROSS.
